CLAIM

The ornamental design for a one-piece cone-shaped reflector trim for recessed light housing, as shown described.

DESCRIPTION

FIG. 1 is a perspective view of the one-piece cone-shaped reflector trim for recessed light housing, showing my design.

FIG. 2 is a top plan view;

FIG. 3 is a bottom plan view;

FIG. 4 is a side elevational view when viewed from the left side;

FIG. 5 is a side elevational view when viewed from the right side;

FIG. 6 is a front elevational view; and,

FIG. 7 is a rear elevational view.
